ELECTRIC SWITCH

Hermon L. Van Valkenburg, Wauwatosa, and Carl A. Schaefer, Whitefish Bay, Wis., assignors to Square D Company, Detroit, Mich., a corporation of Michigan

Application May 6, 1943, Serial No. 485,794

19 Claims. (Cl. 200—116)

1

This invention relates to electric switches, and more particularly to electric switches manually operable at will to open and closed positions and automatically operated to open position in response to current overloads, such as are used for the protection and control of electric motors.

An object of the invention is to provide a manual and automatically operable electric switch having an improved and reliable operating mechanism for the manual and automatic operation.

Another object of the invention is to provide an automatic and manually operable electric switch having current responsive means in a plurality of poles, and a latched tripping member in which occurrence of a current overload in any one of said current responsive means will effect unlatching of the tripping member from the plurality of current responsive means.

Another object of the invention is to provide a manually and automatically operable electric switch in which the operating mechanism includes an operating part normally latched for movement in a restricted path for manual operation and with the operating part releasable on overload for automatic movement out of said path to effect opening movement of the switch.

Another object of the invention is to provide a manually and automatically operable electric switch in which the operating mechanism includes a double toggle arrangement with one of the toggles effective for manual operation and with the other toggle releasable upon the occurrence of a current overload to effect automatic tripping of the switch.

Other objects and features of the invention will be readily apparent to those skilled in the art from the specification and appended drawings illustrating certain preferred embodiments in which:

Figure 1 is a plan view of the electric switch according to the present invention with parts broken away and with the enclosing box removed.

Figure 2 is a vertical sectional view on the line II—II of Figure 1, showing the parts in manual "off" position.

Figure 3 is a sectional view in a plurality of planes along the lines III—III in Figure 2.

Figure 4 is a sectional view in a plurality of planes along the lines IV—IV of Figure 2.

Figure 5 is a partial detail sectional view on the line V—V of Figure 4.

Figure 6 is a partial view similar to Figure 2 showing the mechanism in the contacts engaged position.

Figure 7 is a partial sectional view similar to

2

Figures 2 and 6, but showing the mechanism in automatically tripped position.

Figure 8 is a partial sectional view similar to Figure 6, but showing a slightly modified form of the invention.

Figures 9, 10 and 11 are diagrammatic views showing, respectively, the "on," "off" and "tripped" positions of the mechanism of Figure 8.

10 Figure 12 is a partial sectional view similar to Figure 6, but showing a further modified form of the invention.

Figures 13, 14 and 15 are diagrammatic views showing, respectively, the "on," "off" and 15 "tripped" positions of the mechanism of Figure 12.

The electric switch according to the present invention comprises an insulating base 1 upon which the conducting parts and operating mechanism are mounted. Against the bottom face of the insulating base is disposed an insulating fiber sheet 2 and upon the opposite side of the fiber sheet 2 is a metallic mounting plate 3 rigidly secured to the base 1 by studs 4, mounting plate 3 being rigidly secured to the back wall 5 of an enclosing box by the studs 6. At the upper or switching end of the base 1, within recessed chambers in the base, are mounted conducting straps 7, shown more particularly in Figure 2, carrying at their front ends terminal portions 8 for the connection of circuit wiring and with their back portions carrying contacts 9. The conducting straps are rigidly secured to the base by studs 11 and the portions 8 are provided with terminal 30 screws 12. For each pole of the frame there is provided an additional stationary contact 13 mounted upon conducting straps 14 in the case of the two outer poles and upon conducting straps 15 in the case of the two inner poles. The conducting straps 14 extend forwardly and end in terminal plates 16 adapted for connection to the current responsive overload units to be connected in the two outer poles of the switch. At the bottom of the base are mounted circuit terminals 17 for the outer poles and 18 for the inner poles of the switch. The terminals 17 extend inwardly into spaced relation with the bars 16, also for connection to the current responsive units, and the terminals 18 extend downwardly into engagement 40 with the conducting straps 15. The stationary contacts 9 and 13 are bridged by a conducting plate 19 carrying contacts 21 and 22. The plates 19 being mounted for movement within guides 23 containing contact pressure springs 24 biasing the switching plates 19.

45

40

45

50

The current responsive units comprise insulating body portions 25 within which are secured elongated cylindrical cups 26 in which are disposed shafts 27 carrying at their outer ends ratchet wheels 28. About the elongated cups 26 are insulating spools 29 about which are wound resistance heating elements 31. The opposite interior ends of the body portions 25 are provided with conducting elements 32 to which the opposite ends of the resistance heating coils 31 are attached and which are connected to conductors 16 and 17 by studs 33 to place the heating coil in series circuit with the outer poles of the switch. Mechanical restraining strips 34 are provided having portions extending in front of the ratchet wheels 28 to prevent longitudinal movement of shafts 27. Between the shafts 27 and cup 26 is disposed a relatively low melting point alloy in conventional manner, this alloy in its solidified condition preventing rotation of the ratchets 28; but when heated to softening temperature by resistance coils 31, permitting the ratchet wheels to rotate.

The operating mechanism for the switch is mounted upon a frame constituted by side plates 35 joined together at the bottom by a bridging plate 36, having a plurality of notched ears 37 extending through slots in the plates 35. A cylindrical spacer 38 is provided at an upper corner of the plates and a pair of outer insulating sheets 39 interlock with the ears 37 to maintain the assemblage of plates 35 and 36, these insulating plates 39 and the cylindrical spacer 38 being maintained in position by means of studs 41 threaded into the spacer, as more particularly shown in Figure 4. An insulating sheet 30 is disposed beneath the plate 36 and the frame assemblage is mounted in the base by means of studs 40 threaded into the plate. A pivot pin 42 is supported in the side plates 35 and carries a plurality of pivotal elements thereon, the outer two being arms 43 which extend upwardly toward the switching end of the base and there joined together by a bridging plate 44 to which is mounted an insulating cross bar 45 by means of a stud 46. The cross bar 45 is provided with a projecting post 47 for each pole of the breaker and upon the post 47 are mounted the guides 23 for the bridging contact plates 19. It is thus seen that the main switching operation is performed by the movement of the contact plates 19 as the arms 43 rotate about the pivot 42.

A main operating spring 48 is disposed between the bottom plate 36 and the arms 43 and biases the arms at all times for rotation in a clockwise direction to move the contact plates 19 to the contacts disengaged position.

Also mounted upon the pivot pin 42 by a spacer bearing 49 in a bell crank lever 51 having one end pivoted at 52 to a link 53, the opposite end of the bell crank 51 being disposed loosely within a slot in a floating insulating plate 54, guided for movement within slots 55 in the plates 35 and 39. The frame plates 35 are provided with integral extensions 56 bridged by a pin 57 to which is secured one end of a tension spring 58, whose other end is connected to the insulating plate 54 and biases the plate toward the back of the base. The opposite ends of the plate 54 are provided with latch elements 59 carrying latching projections 61 adapted to engage with and be retained by the teeth on ratchet wheels 28. As more particularly shown in Figures 3 and 4, the ratchet wheels 28, when in normal non-rotating condition, will sup-

port the plate 54 in its forward position with the bell crank 51 latched in its position of maximum clockwise rotation.

At the outside of the frame plates 35, by means of a pin 62 bridging the same, are pivotally mounted a pair of arms 63 which extend forwardly and at their forward ends are rigidly connected to an operating handle 64 as by means of rivets 65. Adjacent their forward ends the arms 63 are bridged by pivot pin 66 upon which, between two spacers 68, is pivotally mounted a link 67. To the link 67 by a pivot pin 68 is pivotally connected a link 69. To the opposite end of the link 69, by pivot pin 71, is pivotally connected a link 72 whose opposite end is pivotally connected by a pin 73 to the main contact operating arms 43. The link 53 which is pivotally connected at 52 to an end of the bell crank 51 has its opposite end pivotally mounted on the pivot 71 joining the links 69 and 72. Also mounted upon pivot pin 42 is a link 74 pivoted adjacent to its opposite end to the pivot pin 68, but having an end extension 75 constituting a stop engaged by spacer 66 in the "on" position of the switch mechanism as in Figure 6. The links 67, 69 and 72 in effect form a pair of toggles, with the link 67 forming one toggle which is effective in the manual operation of the switch and with the links 69 and 72 forming a second toggle which is effective in the automatic tripping of the switch. The link 53 is provided with a surface 76 engaged by spacer 66 to effect the resetting or relatching of the plate 54 after an automatic opening operation.

The toggle formed by the links 69 and 72 is normally maintained in the relationships shown in Figures 2 and 6, by means of link 53 which interconnects the pivots 71 and 52. The bell crank 51 is normally maintained stationary due to the maintenance of plate 54 in latched position by the ratchet wheels 28 and, accordingly, the pivot 52 is normally maintained in a fixed position; hence, the pivot 71 is limited in its motion in manual operation to an arc about the pivot 52, the link 53 thus normally preventing collapse of the links 69 and 72.

The link 74 interconnects fixed pivot 42, and pivot 68; therefore, the pivot 68 is limited in its movement at all times to an arc about the pivot 42 as a center.

In the manual operation of the switch, the parts, as shown in Figure 2, are in the normal "off" position. If the handle 64 is rotated in a counterclockwise direction about pivot 62, the link 67, which is connected to the arms 63 supporting the handle, will force pivot 68 downwardly in an arc about pivot 42. Link 69 will, thereupon, force pivot 71 downwardly in an arc about pivot 52; link 72 will thus effect rotating of the contact operating arms 43 in a counterclockwise direction to engage contacts 21 and 22 with stationary contacts 9 and 13 and complete the circuits through the poles of the switch. This movement of the operating handle 64 is stopped, as shown in Figure 6, by engagement of a spacer 66 with the end 75 of link 74 at which time the link 67 is overcenter with respect to the line of force exerted by the main operating spring and, accordingly, the parts are in a stable position with the contacts engaged. To manually open the contacts a reverse action is effected, the handle 64 being rotated in a clockwise direction until the link 67 passes through the centerline of the force exerted by the main operating spring 48, whereupon the parts are moved to the posi-

5

tion of Figure 2 under the bias exerted by the spring.

Upon the occurrence of an overload through either or both of the heating coils 31, the associated tripping unit will become active through the softening of its holding alloy and permit rotation of the associated ratchet wheel 28. As this ratchet wheel rotates, the associated latch 61 moves downwardly out of engagement therewith, permitting counterclockwise rotation of the bell crank 51. As this movement continues, the plate 54 is rotated and the unlatched latching portion 61 will be moved sideways toward the interior axis of the switch until it is disengaged from its associated ratchet, whereupon the plate 54 moves bodily toward the back of the base carrying the bell crank 51 to its maximum counterclockwise position, as shown in Figure 7. This movement of the bell crank moves the pivot 52 toward the left and collapses the toggle formed by links 69 and 72 into the position of Figure 7, by the contacts separating under the action of the main spring 48 and the trip latch spring 58.

In this movement of the parts to the automatically tripped position with the collapse of the linkage 69-72, a small biasing force is exerted on the operating handle to move it a short distance in a clockwise direction to a position intermediate its "on" and "off" positions in which it indicates the automatic opening of the circuit.

It is apparent that since the toggle represented by the link 69-72 is not fully made, the mechanism will operate to open the contacts if the main spring 48 is made sufficiently strong and the spring 58 is omitted entirely. However, to speed up the opening movement of the switch mechanism and to make this operation more reliable, the biasing spring 58 to more positively collapse the toggle is utilized.

The insulating body portions 25 of the operating units interlock with the base 1, as shown, to form chambers about the resistance coils 31 which are closed against egress of flame occurring upon the burning out of these coils except for a vent 77 leading through the base and venting to the exterior at the sides thereof adjacent the back. The burning out or fusing of the resistor coils may occur upon occurrence of a heavy short circuit through the switch which the attendant fuses may not clear with sufficient speed to prevent damage to the resistors. With the arrangement shown, the vapor and flame which result from such burn-out are successfully vented without the emission thereof to the outside of the box enclosing the switch.

With the parts in the automatically tripped position of Figure 7, it is necessary to reset the switch mechanism by relatching the plate 54 in its forward position before the contacts may be manually closed. This operation is effected by moving the switch handle 64 to the "off" position in a clockwise direction from the position shown in Figure 7 to the position of Figure 2. In this movement, a spacer 66 engages the surface 76 on the lever 53 and moves this lever toward the right, thus rotating the bell crank in a clockwise direction and moving the plate 54 forwardly until the latches 61 engage with the ratchet wheels 28 at the opposite sides of the switch. Assuming that the alloy within the tripping unit has, in the meantime, cooled sufficiently to solidify, the ratchets will be maintained in position and the plate 54 latched in its forward position. The parts then assume the position of Figure 2 and the rotation of the handle 64 in a

6

counterclockwise direction will move the bridging contacts into engaged position as previously explained.

In Figures 8, 9, 10 and 11, a slightly modified form of the invention is shown utilizing a single operating spring and securing greater reliability of action than would be secured if the preferred form of the device were utilized without the spring 58. In this construction, the spring 58 is omitted and the link 72 is replaced by a bell crank lever 78, one leg of which performs as in the preferred embodiment the function of the link 72. The other leg of the bell crank 78 terminates in a circular portion 79 which receives the seat 81 for a main operating spring 82 which replaces the operation spring 48 of the preferred embodiment. In this construction, the spring 82 will function as above to rotate the main contact operating arms 43 in the manual operation and upon automatic operation, the toggle formed by the link 69 and the leg of the bell crank will be collapsed under the bias of spring 82 acting on the bell crank lever. In this construction, a single spring 82 replaces the springs 48 and 58 and the collapse of the toggle is effected not only through the force moment represented by its position at one side of dead center position, but also by the force moment exerted through the arm of the bell crank lever. The "on," "off" and "tripped" positions shown diagrammatically in Figures 9, 10 and 11 correspond to the description of operation for the preferred form of the breaker.

Another modification of the manual and automatic switch according to this invention is shown in Figures 12, 13, 14 and 15. The principal distinction over the switch mechanism in Figures 1 through 7 lies in the substitution of a "prop latch" arrangement for the three-link double toggle construction shown in the preferred form. In this arrangement, there is substituted for the link 67 a pair of parallel links 83 pivoted as before on the pivot pin 60, but carrying at their opposite ends a roller 84 mounted on a bridging pivot pin 85 upon which is also pivoted the lever 14. For the links 69 and 72 there is substituted a single link 86 pivoted on the pivot pin 73 and having on its forward surface a trackway 87 engaging with the roller 84. The link 53 is pivoted to link 86 at an intermediate point by the pivot pin 88. The other operating parts of the switch are substantially the same as in the preferred embodiment. In the operation of the switch of Figures 12 through 15, the normal manual movement of the pivot 88 is limited to an arc about pivot 52 by the link 53, thus maintaining the link 86 in a substantially upright position. In the manual operation, the links 83 function substantially in the same manner as the link 67. As the handle is rotated in a counterclockwise direction from the position of Figure 14 to the position of Figure 13, such rotation of the handle moves the pivot 85 of the roller 84 in an arc about pivot 42, thus moving the link 86 downwardly and rotating the main contact arms 43 in a counterclockwise direction into the contacts engaged position of Figures 12 and 13. The manual movement to "off" position is the reverse of that described, link 86 again being maintained in a substantially upright position but moving upwardly as the upper end of the links 83 move to the right into the position of Figure 14. In the automatic operation of this modification, the latch plate 54 is released as previously described and the bell crank 51 is rotated in a counterclockwise direction to move link 53 to the right 75 and rotate link 86 in a counterclockwise direction

about pivot pin 73. In this rotation of the link 86, it is moved beyond the roller 84 so as to be no longer retained thereby, whereupon the movable contacts are free to rotate in a clockwise direction under the action of the main spring 48 into the position shown in Figure 15. The reset operation is similar to that for the preferred embodiment, the surface 76 again being engaged to rotate the bell crank 51 in a clockwise direction to move plate 54 into related position, this movement moving link 53 to the right and replacing link 86 in its substantially upright position where its surface 87 cooperates with the roller 84.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In an electric switch, switching means, an operating handle, a link pivoted at one end to said switching means, a second link pivoted at one end to said operating handle, an intermediate link pivoted to the opposite ends of said first mentioned links, means positively restraining the pivot junctions of said links for normal movement in fixed paths, movement of said handle effecting movement of the link connected thereto to effect movement of said pivot junctions in said fixed paths to move the switching means to open and close the circuit through the switch, and means for effecting movement of at least one of said positively restrained link pivot junctions out of its normal fixed path to a collapsed position in response to the occurrence of a current overload through the switch to effect automatic movement of said switching means to an open circuit position.

2. In an electric switch, switching means, an operating handle, a link pivoted at one end to said switching means, a second link pivoted at one end to said operating handle, an intermediate link pivoted to the opposite ends of said first mentioned links, means positively restraining the pivot junctions of said links for normal movement in fixed paths, movement of said handle effecting movement of the link connected thereto to effect movement of said pivot junctions in said fixed paths to move the switching means to open and close the circuit through the switch, and means for effecting movement of at least one of said positively restrained link pivot junctions out of its normal fixed path to a collapsed position in response to the occurrence of a current overload through the switch to effect automatic movement of said switching means to an open circuit position, and means for effecting movement of said last mentioned link 60 pivot junction into its restrained position in response to movement of the operating handle to effect resetting of the switch mechanism in its normal position.

3. In an electric switch, switching means movable to open and close the circuit through the switch, an operating handle, a linkage interconnecting said switching means and handle, means for effecting movement of said linkage in response to movement of said handle to move 65 the switching means into its circuit closed and circuit open positions, a pair of current responsive elements connected to be responsive to the flow of current through said switch, means engageable with said current responsive elements 70

5 to be latched in a normal stationary position, means normally positively restraining a knee of said operating linkage to movement in a fixed path and maintained in its normal restraining position by said latched means, and means whereby a current overload through either of said current responsive elements will cause release of the latched means to effect movement thereof and of the restraining means to collapse said knee out of its normal fixed path and effect automatic movement of the switching means to open circuit position.

4. In an electric switch, a pair of current responsive elements connected to be responsive to the current flowing through the switch, means bridging said current responsive elements and latched thereby in a normal fixed position, stationary and movable contacts for the switch, manual means for effecting movement of the movable contacts to engaged and disengaged positions, means controlled by said bridging means for effecting the automatic movement of the movable contacts to disengaged position, release of said bridging means by one of said current responsive elements in response to the flow of an overload current therethrough effecting the mechanical release of said bridging means from the other current responsive element and its movement bodily to a position effecting the automatic disengagement of the contacts.

5. In an electric switch, a pair of current responsive elements, means normally latched by said current responsive elements in a fixed position, a bell crank lever engageable with said last mentioned means to be retained thereby in a normal fixed position, a switching member, an operating handle, a linkage interconnecting said switching mechanism and operating handle movable in response to the movement of the operating handle to effect the switching operation, and a lever interconnecting a knee of said linkage and said bell crank, release of said first mentioned means by either of said current responsive elements effecting movement of the bell crank and lever to move the knee of said linkage to collapsed position to effect automatic movement of the switching member to open circuit position.

6. In an electric switch, a pair of current responsive elements connected to be responsive to the current flowing through the switch, means bridging said current responsive element and latched thereby in normal fixed position, means biasing said bridging means for movement to a second position, stationary and movable contacts for the switch, manual means for effecting movement of the movable contacts to engaged and disengaged position, means controlled by said bridging means for effecting the automatic movement of the movable contacts to disengaged position and including means engaging said bridging means and limiting the lateral movement thereof, release of said bridging means by one of said current responsive elements in response to the flow of overload current therethrough resulting in a rotation of the bridging means under the action of its biasing means, this rotation through the means restricting the lateral movement effecting a mechanical release of the opposite end of said bridging means from the other current responsive element and movement of the bridging means bodily to said second position to effect the automatic disengagement of the contacts.

7. In an electric switch, stationary and movable contacts, manual means for effecting move-

ment of the movable contacts to engaged and disengaged positions, and automatic means for effecting movement of the movable contacts to disengaged position in response to the passage of an overload current through the switch and including a pair of solder pot relays having ratchet wheels normally stationary but rotatable in response to the passage of excess current through the relays, a member bridging said ratchet wheels and normally latched thereby in fixed position, and means whereby movement of said bridging member effects operation of the means for automatically opening the movable contacts, movement of said bridging member in response to release by one of said ratchet wheels effecting the mechanical release thereof from the other ratchet wheel and its movement bodily to a position effecting operation of said automatic means.

8. In an electric switch, a switching member, an operating handle, an operating link pivotally connected to said switching mechanism, an operating link pivotally connected to said handle, a roller on said handle link normally engageable with the link on said switching member to effect movement thereof to move the switching member to circuit controlling positions in response to movement of the operating handle, means normally restraining a point on said switching member link for movement in a fixed path, and current responsive means for rendering said restraining means ineffective to effect movement of said switching member link out of said fixed path to an inoperative position to move the switching member to open circuit position.

9. In an electric switch, a switching member, an operating handle, a lever pivotally connected to said switching member, a lever pivotally connected to said operating handle, means connected to said handle lever and restricting its point of connection thereto to movement in a fixed path at all times, means connected to said switching member lever and normally restricting its point of connection thereto to movement in a fixed path, interengaging surfaces on said links normally operatively engageable to effect movement of the switching member in response to movement of the operating handle for manual switching operation, and means responsive to the flow of an overload current through the switch for effecting movement of said switching member link out of operative engagement with said handle link to effect automatic switching movement of the switching member to disengaged position.

10. In an electric switch, switching means movable in a fixed path, an operating handle movable in a fixed path, a link pivotally connected to said switching means, means connected to said link and normally restraining the point of connection thereto to movement in a fixed path, said link having a surface thereon forming a track-way, a link pivotally connected to the operating handle and having a roller on its opposite end cooperating with said track-way, means connected to said handle link and restricting its point of connection thereto to movement in a fixed path, movement of said handle moving said handle link to effect movement of the switching means to its circuit closed and circuit open positions, and means responsive to the flow of an overload current through the switch for effecting movement of said first mentioned link out of its normal fixed path to move its track-way beyond the roller on said handle link to effect automatic movement of the switching means to disengaged position.

11. In an electric switch, a switching member,

an operating handle, an operating lever pivotally connected to said switching member, an operating lever pivotally mounted on said operating handle and directly movable thereby, means for positively transmitting force from one of said levers to the other, means for positively restraining points on said levers other than their said pivotal connection and mounting to predetermined paths of movements, and current responsive means operable upon the occurrence of a current overload through the switch for releasing at least one of said restraining means to effect automatic movement of the associated point out of its predetermined path to its inoperative position, and automatically moving the switching member to open the circuits of the switch.

12. In an electric switch, a switching member, an operating handle, an operating lever pivotally connected to the switching member, an operating lever pivotally mounted on said operating handle and directly movable thereby, means interconnecting said levers, means positively restraining a point on said handle lever other than said pivotal mounting to a fixed path of movement at all times, means normally positively restraining a point on said switching member lever other than said pivotal connection to a fixed path of movement, means for effecting movement of said levers in response to movement of said operating handle with said points positively restrained for movement in said fixed paths to move the switching member to open and close the circuit through the switch, and current responsive means for rendering the restraining means for said switching member lever point ineffective to permit movement thereof out of its fixed path to an inoperative position to effect automatic movement of the switching member to open the circuit through the switch.

13. In an electric switch, a switching member, an operating handle, an operating linkage interconnecting said handle and said switching member, means normally positively restraining a knee of said linkage to a fixed path of movement, means for extending and collapsing said linkage for manual operation of said switching member while said knee moves in said positively fixed path, means for moving said restraining means to move said knee of said linkage out of said fixed path of said movement and effect collapse thereof to automatically move said switching member, and current responsive means for rendering said means for moving said restraining means effective upon occurrence of a current overload through the switch.

14. In an electric switch, a switching member, an operating handle, an operating linkage interconnecting said handle and said switching member, a lever pivotally connected to a knee of said linkage, means providing a pivotal mounting for said lever about which the lever rotates to restrain said knee of said linkage to a fixed path of movement, means for extending and collapsing said linkage for manual operation of said switching member while said knee moves in said fixed path, and current responsive means operable upon the occurrence of a current overload through the switch for effecting movement of the pivotal mounting of said lever to move said linkage knee out of said fixed path of movement to effect automatic movement of the switching member to open position.

15. In an electric switch, a switching member, an operating handle, a linkage interconnecting said switching member and handle, means for

extending and collapsing said linkage upon manual movement of said operating handle to move the switch member and perform the switching operation, means biasing a knee of said linkage for movement to collapse the linkage, and current responsive means normally positively restraining said knee from said collapsing movement and normally positively limiting the knee to a predetermined path of movement during manual operation of the switch, said current responsive means upon the occurrence of a predetermined current overload through the switch effecting the release of said knee for movement out of said predetermined path under said biasing means to effect automatic opening of the circuit through the switch.

16. In an electric switch, a switching member, an operating handle, a linkage interconnecting said switching member and operating handle, means for extending and collapsing said linkage in response to manual movement of said operating handle to perform the switching operation, means biasing a knee of said linkage toward a collapsed position, a lever pivotally connected to said knee and having a normally fixed pivot about which it rotates to restrain said knee from collapsing movement, and current responsive means for effecting movement of said lever mounting to permit collapse of the knee under said bias upon the occurrence of a current overload through the switch to effect automatic opening of the circuit therethrough.

17. In an electric switch, a switching member, an operating handle, a multiple linkage operating said switching member and operating handle, means for collapsing and extending said linkage to effect movement of said switching member in response to movement of said operating handle to effect the switching operation, levers pivotally connected to knees of said linkage and having pivotal mountings about which they rotate to restrict said knees to fixed paths of movements, and means for effecting movement of at least one of said lever mountings to effect movement of at least the associated knee out of its fixed path to a collapsed position upon the occurrence of a current overload through the switch, whereby to effect automatic opening of the circuit.

18. In an electric switch, a switching member, an operating handle, a multiple linkage interconnecting said switching member and said operating handle, a lever pivotally connected to the knee of said linkage adjacent to the operating handle and having a fixed pivotal mounting about which it rotates to limit said knee to a fixed path of movement at all times, a lever pivotally connected to the knee of said linkage adjacent to said switching member and having a normally fixed pivotal mounting about which it rotates to normally limit said second mentioned knee to a

- fixed path of movement, means extending and collapsing the linkage in response to movement of said operating handle to move said knees in said fixed paths to effect movement of said switching member into its operating positions, and means operable upon the occurrence of a current overload through the switch for effecting movement of the pivotal mounting of said second mentioned lever to move the associated knee out of its normal fixed path to collapsed position to effect automatic opening movement of the switching member.
19. In an electric switch, a switching member mounted for oscillation about a fixed pivot, an operating handle mounted for oscillation around a fixed pivot, a multiple linkage interconnecting said switching member and operating handle, a lever pivotally connected to the link adjacent to the operating handle and having a fixed pivotal mounting about which it rotates to limit movement of the adjacent linkage knee to a fixed path at all times, a lever pivotally connected to the link adjacent the switching member and having a normally fixed pivotal mounting about which it rotates to normally limit the adjacent linkage knee to a fixed path of movement, means for moving said linkage in response to movement of said operating handle to effect movement of said knees in said fixed paths to manually move the switching member to circuit closed and circuit open positions, and current responsive means for effecting movement of the pivotal mounting of said second mentioned lever to permit movement of the associated linkage knee to collapsed position to automatically open the switch upon the occurrence of a current overload therethrough.

HERMON L. VAN VALKENBURG.
CARL A. SCHAEFER.
